UNITED STATES PATENT OFFICE.

FRANK R. BELLUCHE, OF MANSFIELD, MASSACHUSETTS, ASSIGNOR TO UNITED PRINTING MACHINERY COMPANY, OF BOSTON, MASSACHUSETTS, A CORPORATION OF MASSACHUSETTS.

ADJUSTABLE FEEDING-TABLE.

1,395,027.

Specification of Letters Patent.

Patented Oct. 25, 1921.

Application filed February 13, 1920. Serial No. 358,348.

To all whom it may concern:

Be it known that I, FRANK R. BELLUCHE, a citizen of the United States, residing at Mansfield, in the county of Bristol and

5 State of Massachusetts, have invented certain new and useful Improvements in Adjustable Feeding-Tables; and I hereby declare that the following is a full, clear, and exact description thereof, reference being 10 had to the accompanying drawings, which form part of this specification.

This invention is a novel improvement in means for feeding sheets of paper to mechanisms for operating thereon; and is particularly designed for use in connection with printing presses having a rotary impression cylinder to which the sheets are to be fed from a feed board or table, either automatically or by hand.

20 The primary object of the invention is to enable the feed board to be readily moved out of the way when it is desired to obtain access to the impression cylinder for any purpose such as making ready. To this end I mount the feed board in such manner that it can be shifted endwise inward over the cylinder and toward the delivery end of the press, so that the pressman can have 25 unobstructed access to the cylinder at the feed end of the press.

A secondary object of the invention is to also mount upon such movable feed board some or all of the various devices for feeding sheets to the cylinder; for front registering the sheet; for side registering the sheet; the front sheet stops, etc., so that when the feed board is shifted out of the way such of the sheet manipulating or controlling devices as are mounted on said 35 board will also be moved therewith out of the way of the pressman, thus facilitating 40 making ready the cylinder or forms at the feed end of the press.

Other minor objects of the invention and 45 advantages thereof will be hereinafter mentioned.

In the accompanying drawings I have conventionally illustrated part of a printing press, and a feed board connected therewith 50 so as to be adjustable out of the way in the manner above stated; and I have also conventionally illustrated various sheet feed-

ing and registering devices, and sheet stops or gages, mounted on the feed board and adjustable therewith.

I will explain the invention with reference to the said drawings to enable others skilled in the art to adapt and use the invention; and in the appended claims summarize the essentials of the invention and 60 the novel details of construction and novel combinations of parts for all of which protection is desired.

In said drawings:

Figure 1 is a conventional side elevation 65 of part of a printing press and an adjustable feed board mounted in accordance with the invention, the feed board being shown in operative position in full lines and shown in dotted lines moved out of the way to permit access to the cylinder.

Fig. 2 is a similar view illustrating another embodiment or adaptation of the invention.

In the drawings 1 represents the impression cylinder of a sheet printing press which may be of any desired kind. The cylinder is provided with grippers to take the sheets in the usual manner. This impression cylinder may coöperate with a plate cylinder, or 75 other suitable member carrying the printing surfaces against which the sheets are to be impressed by the impression cylinder. In the drawings the press indicated is a bed and cylinder printing press, which may be of any 80 well known type.

At one side of the cylinder 1 is the feed board 2, which may be of any desired type, and is so mounted that it can be readily moved endwise from the operative or feed- 90 position indicated in full lines in Figs. 1 and 2, to inoperative or out of the way position; (indicated in dotted lines in Figs. 1 and 2).

In Fig. 1 this feed board is shown as supported by rollers 2^a at its front end upon supporting bars 9 attached to the side members of the press and which extend rearwardly from the cylinder toward the delivery end of the press.

The outer end of the feed board may be supported in any suitable manner so that it can be bodily moved as described. As shown in Fig. 1 the outer end of the feed

board is supported upon swingable levers 3 which are pivoted at 3^a to the sides of the press, and the upper ends of the levers have a sliding engagement (as at 3^b) with slotted members 2^b on the feed board.

The drawings simply conventionally show one means or mode of supporting the feed board so that it can be moved longitudinally over the cylinder from the operative position to the out of the way position; and I do not consider the invention restricted to any particular means of mounting the feed board so as to be capable of such adjustments.

15 The feed board is normally supported at the feed end of the press as shown in full lines (Figs. 1 and 2), so that the sheets can be supplied directly from the feed board to the impression cylinder in the usual manner; 20 but when the operator desires to make ready the press, or to get at the impression cylinder, he can move the feed board endwise directly over the cylinder 1 into the out of the way position, indicated in dotted lines 25 in Figs. 1 and 2, thus giving the operator free access to the cylinder from the feed end of the press. This mode of adjusting the feed board I consider broadly novel.

30 A subsidiary feature of the invention, but one of material practical importance, is having the feed board carry some or all of the sheet feeding and controlling devices.

35 As indicated in Fig. 1, the front guides or sheet-stops 4 may be operatively supported upon the inner end of the feed board and be removable therewith into or out of operative position. Also as indicated in Fig. 1, the feed board may carry the bank or pile 40 of sheets S; a sheet separator 5; bank clamps 6; bank stop 7; a reciprocating sheet feeder 8; and suitable side registering devices 11; and also means such as tapes 10, for feeding the bank of sheets forward against the bank stop 7. Each and all of 45 such devices as are mounted upon the feed board should be suitably timed and operated.

50 The general arrangement of the sheet handling mechanisms such as indicated in Fig. 1 on the feed board however may be such as shown in my application (Case 6415); but the particular construction of such devices forms no part of the present invention; and as there are various other such devices 55 known to those familiar with the art that could be readily mounted on the feed board, they are not described nor shown in detail.

60 It will be seen that such of the sheet handling devices as are operatively mounted upon the feed board will be moved therewith into or out of operative position. I consider the invention to include in its scope 65 mounting upon the feed board itself (so as to be movable therewith) any one or more of the mechanisms for feeding the sheet, or

for positioning the sheet or for front registering the sheet, or for side registering the sheet. Obviously having such devices mounted on and movable with the feed board into or out of operative position will 70 greatly facilitate the operation of making ready the press or impression cylinder.

In the form illustrated in Fig. 2 the rear end of the feed board 2 is shown as supported by levers 3^a pivoted at 3^b to the frame 75 and at 3^c to the board, and in this instance the feed board instead of carrying the pile or bank of sheets (as indicated in Fig. 1) may carry suitable mechanism to convey the sheets from a sheet feeder P of any suitable 80 kind to the cylinder.

When the feed board shown in Fig. 2 is in operative position it is adapted to receive sheets successively from the usual feeder P, by which the sheets are successively 85 fed onto the feed board.

The feed board in Fig. 2 is shown as provided with coating tapes 10^a, 10^b that move the sheets forward thereon; although any other suitable forwarding means may be 90 used. The board shown in Fig. 2 may also carry the front sheet stops 4, and side registering devices 11, if desired; and such of these devices as are mounted on the feed board would be movable therewith from the 95 position indicated in full lines in Fig. 2 to the position indicated in dotted lines in Fig. 2.

As stated, the drawings simply conventionally illustrate the invention, but from 100 such drawings and the foregoing description anyone skilled in the art can understand the invention and readily adapt and use the same. The essentials of the invention are (1) having the feed board longitudinally 105 movable from operative position at one side of a cylinder to out of the way position at the other side of the cylinder; and (2) having such board carry one or more or all 110 of the sheet separating devices, sheet feeding devices, sheet registering devices, and sheet stops or gages.

What I claim is:

1. In a sheet printing press having impression means; a feed board longitudinally movable over the printing means and adjustable from operative feeding position adjacent one side of the printing means to inoperative position adjacent the opposite side of said means. 115

2. In a printing press having impression means; a feed board longitudinally adjustable from operative position at the feed side of the impression means over said means to out of the way position adjacent the delivery end of the press. 120

3. In a printing press having an impression cylinder; a feed board from which the sheets are fed to the cylinder, said feed board being movable longitudinally over the 130

cylinder from feeding position to out of the way position at the delivery side of the cylinder.

4. In a printing press having an impression cylinder; a movable feed board, means for normally supporting said board in operative position at the feed side of the cylinder; and means for supporting said feed board in out of the way position at the delivery side of the cylinder.

5. In combination with a printing press having an impression cylinder; a movable feed board, means for normally supporting said board at the feed side of the cylinder when in operative position; and means for supporting said feed board at the delivery side of the cylinder in out of the way position, said feed board being longitudinally movable to either position.

20 6. In combination with a printing press having an impression cylinder, a feed board longitudinally adjustable from operative position at the feed side of the cylinder over the cylinder to out of the way position adjacent the delivery end of the press; means for supporting the feed board in operative position; and means for supporting the feed board in out of the way position.

7. In combination with a printing press 30 having an impression cylinder; a feed board; tracks supporting one end of the feed board when in operative position; said tracks extending rearwardly of the cylinder toward the discharge end of the press to support the feed board in out of the way position; and means for supporting the front end of the feed board when in operative position, said feed board being longitudinally movable from feeding position 35 in front of the cylinder to out of the way position in rear of the cylinder.

8. In a sheet printing press having impression means; a feed board longitudinally movable over the printing means and adjustable from operative feeding position adjacent one side of the printing means to out of the way position adjacent the opposite side of said means; with sheet positioning devices mounted on said feed board 50 and movable therewith.

9. In a printing press having an impression cylinder; a movable feed board, means for normally supporting said board in operative position at the feed side of the cylinder; and means for supporting said feed board in out of the way position at the delivery side of the cylinder; with sheet feeding devices mounted on said feed board and movable therewith.

60 10. In a printing press having impression means; a feed board longitudinally adjust-

able from operative position at the feed side of the impression means over said means to out of the way position adjacent the delivery end of the press; with sheet feeding devices and sheet positioning devices carried by said feed board and movable therewith.

11. In combination with a printing press having an impression cylinder, a feed board longitudinally adjustable from operative position at the feed side of the cylinder over the cylinder to out of the way position adjacent the delivery end of the press; means for supporting the feed board in operative position; and means for supporting the feed board in out of the way position; with sheet feeding devices and sheet registering devices carried by said feed board and movable therewith.

12. In a sheet printing press having impression means; a feed board longitudinally movable over the printing means from the feeding position to out of the way position; with sheet feeding devices, sheet registering devices; and sheet stops, carried by said feed board and movable therewith.

13. In a printing press having an impression cylinder; a movable feed board, means for normally supporting said board in operative position at the feed side of the cylinder; and means for supporting said feed board in out of the way position at the delivery side of the cylinder; with sheet feeding devices, sheet registering devices; and sheet stops, carried by said feed board and movable therewith.

14. In a printing press having impression means; a feed board longitudinally adjustable from operative position at the feed side of the impression means over said means to out of the way position adjacent the delivery end of the press; with sheet supporting devices, sheet feeding devices; sheet registering devices, and sheet stops, carried by said feed board, and movable therewith.

15. In combination with a printing press having an impression cylinder, a feed board longitudinally adjustable from operative position at the feed side of the cylinder over the cylinder to out of the way position adjacent the delivery end of the press; means for supporting the feed board in operative position; and means for supporting the feed board in out of the way position; with sheet supporting devices, sheet feeding devices; sheet registering devices, and sheet stops, all carried by said board and movable therewith.

In testimony that I claim the foregoing as my own, I affix my signature.

FRANK R. BELLUCHE.
